US0D1040003S

(12) **United States Design Patent** (10) Patent No.: **US D1,040,003 S**
(45) Date of Patent: ** Aug. 27, 2024

(54) **TIMEPIECE**

(71) Applicant: **Marco Tedeschi**, Le Vaud (CH)

(72) Inventor: **Marco Tedeschi**, Le Vaud (CH)

(**) Term: **15 Years**

(21) Appl. No.: **35/517,906**

(22) Filed: **Jul. 11, 2023**

(80) **Hague Agreement Data**

Int. Filing Date: **Jul. 11, 2023**

Int. Reg. No.: **DM/230348**

Int. Reg. Date: **Jul. 11, 2023**

Int. Reg. Pub. Date: **Jul. 28, 2023**

(30) **Foreign Application Priority Data**

Jan. 24, 2023 (CH) 2023-00036

(51) **LOC (14) Cl.** **10-07**

(52) **U.S. Cl.**

USPC **D10/126**
